UNITED STATES PATENT OFFICE.

ABRAHAM SCHWALBERG, OF BROOKLYN, NEW YORK.

WRIST-WATCH STRAP.

Application filed March 13, 1928. Serial No. 261,229.

This invention relates to wrist watch straps and particularly to that type which is made in two sections, each attachable to one of the ears of the watch and removable attachable 5 to each other, and in which bends are formed for enclosing the watch ears.

My invention contemplates, among other things, the provision of simple and effective means for enclosing the watch ears, and for 10 holding the doubled over ends of the strap sections in place while allowing the quick and easy detachment of the parts from the watch when desired.

The various objects of my invention will be 15 clear from the description which follows, and from the drawings, in which,

Fig. 1 is a perspective view of a wrist watch strap embodying my invention as it appears when passed through the ears of a watch.

20 Fig. 2 is a similar view of a modified form of means for holding one end of one of the strap sections in place.

Fig. 3 is a similar view of the same showing a modification wherein certain stitching is 25 omitted.

Fig. 4 is a similar view of a buckle end of one of the strap sections showing another modification applied particularly to a double buckle.

30 Fig. 5 is a similar view of the same showing another modification.

Fig. 6 is a similar view of the same showing still another modification.

Fig. 7 is a similar view of one end of the 35 buckle section showing particularly how the metal loop is secured to the strap section, and

Fig. 8 is a similar view of part of the perforated section showing the means for securing the metal loop thereto.

40 In the practical embodiment of my invention which I have illustrated, the strap consists of two sections 10 and 11, the former section being designated as the "perforated" section herein and the latter section being designated hereinafter as the "buckle" section.

45 One or both of said sections, as usual may be made with a finished face and an unfinished face, it being intended that the unfinished face be hidden either by suitable bending or overlapping of the sections or on the inside thereof and against the wrist of the wearer. The wrist watch is indicated by the numeral 12 and as usual is provided with ears 13 and 14 which are engaged by the respective strap 50 sections, and removably held therein by bends in the sections adjusted to enclose the watch

ears by means of metal loops suitably secured to the sections.

One end 15 of the perforated section 10 is provided with perforations as 16, and is 60 adapted to be passed through the frame of the buckle 18 for engagement by the tongue 17 thereof. However if a tongueless buckle, of any well known type is used, the perforations 16 may be omitted, the end 15 being 65 held in place by the swinging member of the buckle in the usual manner. The other end of the perforated section is bent back on itself for a short distance to form an opening 19, in which the loop 20 of metal or other 70 suitable material is held, as illustrated in Fig. 7. In order to decrease the thickness or in other words to flatten the bent end 21 of the perforated section, if desired, I 75 may provide the stitching 22 in close proximity to the bend, in addition to the stitching 23 on the other side of the loop 20, though it will be understood that throughout staples may be substituted for any of the stitching and that the stitching 22 may be 80 omitted as shown in Fig. 1. It will be noted that the end flap 24 forming the bend 21, is 85 bent on to the unfinished face of the perforated section 10, whereby the loop 20 is prevented from coming in contact with the wrist of the wearer.

I prefer to make the depth of the loop 20 such, that there is just room enough therein for the flap 24 and for the body portion of the perforated section 10 to pass therethrough, so that there is left little or no room for displacement. To secure said section in 90 place about the ear 14, the end 15 is passed through the ear from the inner or wrist side to the outer side and then through the loop 20, thereby forming the bend 21 hugging the ear 14 when the section 10 is pulled through the loop a sufficient distance to bring the loop 95 close to the ear.

The buckle section 11 is also preferably provided with a metal loop 27 suitably held on to the inner or unfinished face of the inner length 28 of said section, as by means of a short piece of material 29, or staples or other suitable means. Where the strip 29 is used, it 100 is held to the unfinished face of the length 28 as by means of the lines of stitching 30 and 31 arranged about midway of the ends of the section 11.

As illustrated in Figs. 1, 2 and 3, the buckle 110 element 18 takes the form of what is known as a single buckle, wherein the tongue 17 is

hinged to one of the outer cross members 32 of the buckle. Where a single buckle is used the end 15 of the perforated section 10, being otherwise loose should be removably securable 5 in place, and this is preferably accomplished by the loop 33, which is also preferably made of metal. The buckle-holding flap 34 at the end of the length 28 is slotted as at 35 to allow the tongue 17 to project therethrough 10 and the flap is seamed in place about the cross member 32 as by means of the stitching 36 whereby the buckle is securely held in position. It will be noted that in the length 28, the finished surface 37 thereof is arranged adjacent 15 to the wrist while the inner or unfinished face 38 is hidden from view by the integral length 39 of the buckle section.

It will also be seen that the buckle is secured in reversed position on the length 28, or in 20 other words, that the tongue member 17 is on the same side of the buckle frame as is the unfinished or inner surface 38, and is arranged to swing away from the wrist. The length 39 of the buckle section 11 is passed through 25 the ear 13 of the watch from the inside to the outside thereof and through the loop 27 thereby forming the bend 40 constricted by said loop in which bend the ear is securely held against displacement.

30 Means are provided for holding the otherwise free end of the length 39 removably in position. As illustrated, said means takes the form of a hook, adapted to pass through a suitable slit or perforation near the end of the 35 length 39. Referring now to Fig. 1, I have there shown a hook member 41 preferably formed of sheet metal and having a hooked end 42 adapted to pass through the slit or perforation 43 in the end of the length 39. In 40 the form illustrated, one end of the hook member is bent about the central part of the enclosed portion of the loop 33, and the body of the member passes through a slot 35 in the flap 34. Stitching as 45 may serve to secure the 45 end of the flap in position, and at the same time aid in preventing detachment of the loop 33 though it will be understood that said stitching may be entirely omitted if desired as indicated in Fig. 3. The slot 35 alone in 50 that case, serves to prevent loss or movement of the loop 33 and of the hook 41 secured thereto. In the construction shown in Figs. 1 and 4, the hook part of the hook 41 is hidden when the strap is assembled, and only a flat 55 band is visible.

As illustrated in Figs. 2 and 3, the hook end 42 may be bent outwardly instead of inwardly so that only the end parts of the hook are visible when the strap is worn.

60 Referring now to Figs. 4, 5 and 6 I have there shown a double buckle 46 secured in place at its intermediate cross bar 47, by means of the flap 34, so that the frame 48 of the buckle may swing about said cross bar. 65 Since one end of the frame of the double

buckle serves to keep the end 15 of the strap down in place, the loop 33 may there be entirely dispensed with, and the hook member 41 secured in place independently of the loop. In Fig. 4 I have shown a pin or bar 49, inserted between the flap 34 and the inner face 38 of the length 28, and integral with the hook 41, or of a separate piece as desired, stitching 45 being used or omitted as may be desired. In Fig. 5 I have shown the hook 41 70 held in place by a suitable flange or eyelet 50 passing through the flap 34 and the length 28, or through either alone, if desired. The eyelet 50 may be made integrally with the remainder of the hook member or it may be 75 made in a separate piece, as is well known, and need not therefore be described in detail. In Fig. 6 I have shown the hook member 41 provided with an enlarged base 51 from which the prongs 52 project. Said base may 80 be arranged between the flap 34 and the inner face 38, and forced through the said flap or through suitable slits therein, and then bent over on to the outer face of said flap thereby securing the hook 41 in position. It will be 85 seen that I have provided a simple, inexpensive, though efficient wrist watch strap easily removable and attachable to the watch ear and simple and effective means easily secured in 90 position for removably securing the otherwise free doubled over end of a section in place with a minimum of labor and materials. 95

While I have shown and described certain possible embodiments of my invention in detail, I do not intend to limit myself thereto, since various changes therein will be apparent to those skilled in the art, but I intend to claim my invention as broadly as may be permitted by the scope of the prior art and the 100 terms of the appended claims. 105

I claim:

1. In a wrist watch strap, a buckle section adapted to be passed through the ear of a watch and having an opening in one end, a buckle secured at the other end of said section, and a hook secured to the buckle end of the section, adapted to pass through the opening at the other end of the section. 110

2. In a wrist watch strap, a buckle section adapted to be passed through the ear of a watch and having an opening at one end, a buckle secured at the other end, a close fitting metal loop on the buckle section intermediate of the ends thereof, and a hook secured to the section near the buckle and adapted to pass through said opening on the doubling of said section back on itself and through the loop and the ear, whereby said loop cooperates with that part of the section adjacent thereto to removably secure the section to the ear. 120

3. In a wrist watch strap, a buckle section adapted to be passed through the ear of a watch and a buckle secured in reversed position at one end of said section, and means including a hook spaced from and independent 125

of the buckle for removably holding the extremity of other end of the section when the section is doubled back on itself after being passed through the ear to bring said extremity 5 into engagement with the hook.

4. In a wrist watch strap, a buckle section adapted to be passed through the ear of a watch and then bent back on itself, a buckle at one end of said section, a flap bent over the buckle for maintaining the buckle in place, means for securing the flap to the remainder of the section, a hook holding member between the flap and the adjacent part of the section and a hook on the member adapted to engage 10 the other end of the section.

5. In a wrist watch strap, a section adapted to be doubled on itself and removably secured at both ends and having an opening at one end, a hook at the other end for reception in 20 the opening and a close fitting metal loop on said section for forming an openable bend therein for holding the ear of a wrist watch in the bend when the end of the section is passed through the ear of the watch and 25 through the loop and then about the hook.

6. In a wrist watch strap, a fastener section adapted to be removably secured to the ear of a watch and designed to be folded back on itself, a flap integral with the section and bent back on the section at one end thereof, and a hook arranged in predetermined position 30 at said flap and adapted to engage the other end of said section.

7. In a wrist watch strap, a section of a 35 single thickness of material, a flap at one end thereof folded back on said section, a hook permanently secured to the section at said flap, said flap being slotted to permit the passage of the hook therethrough, and an elongated cross member interposed between the flap and the remainder of said section and across the slot, said hook being pivotally mounted on said elongated member.

8. In a wrist watch strap, a section of a 45 single thickness of material, a buckle holding flap at one end of the section integral with and folded back on to the remainder of the section, a hook member arranged in predetermined position at said flap and having a 50 hook at one end thereof, and means at the other end of the hook member for permanently securing the hook member in position to said section at the flap, the hook of said hook member being adapted to pass through the other end of the section on the doubling 55 of said section back on itself.

9. In a wrist watch strap, a section adapted to be bent back on itself after the passage 60 thereof through the ear of a watch, and having a perforation at one end thereof and an integral buckle holding flap folded over at the other end thereof, a hook member spaced from the end of the flap and having a hook at one end thereof adapted to pass 65 through said perforation, and means at the other end of the hook member passing underneath said flap and permanently securing the hook member to said section.

10. In a wrist watch strap, a buckle section, a folded buckle holding flap on said section having an opening therein, a loop having one side thereof inserted between the flap and the remainder of the section, and a hook member mounted on said side of the 70 loop passing through said opening.

11. In the buckle section of a two section 75 wrist watch strap, a buckle secured at one end of said buckle section, said section having an opening at one end thereof and a hook 80 at that end of the section opposite said opening and adapted to be passed through said opening for automatically holding said section in doubled-over position throughout the length of the section and thereby leaving 85 the buckle free for the reception of the other strap section.

ABRAHAM SCHWALBERG.
